US00D738034S

(12) **United States Design Patent**
Wilcox et al.

(10) **Patent No.:** **US D738,034 S**
(45) **Date of Patent:** **** Sep. 1, 2015**

(54) **LIGHTING APPARATUS**

- (71) Applicant: **Cree, Inc.**, Durham, NC (US)
(72) Inventors: **Kurt S. Wilcox**, Libertyville, IL (US);
John W. Durkee, Raleigh, NC (US);
James Michael Lay, Apex, NC (US)
(73) Assignee: **Cree, Inc.**, Durham, NC (US)

(**) Term: **14 Years**

(21) Appl. No.: **29/492,522**

(22) Filed: **May 30, 2014**

Related U.S. Application Data

- (63) Continuation-in-part of application No. 13/842,521, filed on Mar. 15, 2013, and a continuation-in-part of application No. PCT/US2014/013937, filed on Jan. 30, 2014.

(57) **CLAIM**

The ornamental design for a lighting apparatus, as shown and described herein.

DESCRIPTION

FIG. 1 is a top isometric view of an ornamental design for a lighting apparatus;

FIG. 2 is a bottom isometric view of the lighting apparatus of FIG. 1;

FIG. 3 is a front elevation view of the lighting apparatus of FIG. 1;

FIG. 4 is a back elevation view of the lighting apparatus of FIG. 1;

FIG. 5 is a left elevation view of the lighting apparatus of FIG. 1;

FIG. 6 is a right elevation view of the lighting apparatus of FIG. 1;

FIG. 7 is a top plan view of the lighting apparatus of FIG. 1; and,

FIG. 8 is a bottom plan view of the lighting apparatus of FIG. 1.

The broken lines (where present) in all FIGS. illustrate portions of the lighting apparatus that form no part of the claimed design.

1 Claim, 4 Drawing Sheets
